US00D827452S

(12) **United States Design Patent** (10) Patent No.: **US D827,452 S**
(45) Date of Patent: ** Sep. 4, 2018

(54) **FOOD CONTAINER**

(71) Applicant: **ZUME Pizza, Inc.**, Mountain View, CA (US)

(72) Inventors: **Julia Collins**, San Francisco, CA (US); **Casper W. Chiang**, Danville, CA (US); **Chester Wajda**, San Francisco, CA (US)

(73) Assignee: **ZUME, Inc.**, Mountain View, CA (US)

(**) Term: **15 Years**

(21) Appl. No.: **29/618,670**

(22) Filed: **Sep. 22, 2017**

Related U.S. Application Data

(62) Division of application No. 29/574,802, filed on Aug. 18, 2016, now Pat. No. Des. 806,575.

Primary Examiner — Lauren R Calve

(74) Attorney, Agent, or Firm — Seed IP Law Group LLP

(57) **CLAIM**

The ornamental design for a food container, as shown and described.

DESCRIPTION

FIG. 1 is a top isometric view of a food container showing our new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

Stippling and tangency lines in the drawings represent the three-dimensional contours of the design, and are not intended to indicate surface decoration.

1 Claim, 5 Drawing Sheets
